UNITED STATES PATENT OFFICE.

DONALD S. KRAMER, OF COLUMBUS, OHIO.

ELECTRIC TYPE-METAL HEATER FOR LINOTYPE-MACHINES.

1,058,184.

Specification of Letters Patent.

Patented Apr. 8, 1913.

Application filed April 9, 1912. Serial No. 689,546.

To all whom it may concern:

Be it known that I, DONALD S. KRAMER, a citizen of the United States, residing at Columbus, in the county of Franklin, State of Ohio, have invented certain new and useful Improvements in Electric Type-Metal Heaters for Linotype-Machines; and I do hereby declare the following to be a full, clear, and exact description of the invention, such as 10 will enable others skilled in the art to which it appertains to make and use the same.

My invention relates to new and useful improvements in type metal heaters for linotype machines and more particularly to electrical heaters and the object of my invention is to provide a type metal heater having a primary and secondary winding, the heat being generated by a current induced in the secondary winding by the passage of an alternating current through the primary winding.

A further object of my invention is to provide an automatic, thermo actuated cut off for regulating the heat generated. And a 25 still further object of my invention is to improve the construction and increase the efficiency of devices of the above described character.

With these and other objects in view, my invention will be more fully described, illustrated in the accompanying drawings which show a preferred embodiment of my device and then specifically pointed out in the claims which are attached to and form a 35 part of this application.

In the drawings, Figure 1 is a central longitudinal section of my type heater. Fig. 2 is a similar section, the inner shell together with the secondary winding, being shown in 40 elevation. Fig. 3 is a section on the line 3—3 of Fig. 1. Fig. 4 is a section on the line 4—4 of Fig. 3.

Referring more specifically to the drawings, in which similar reference numerals 45 designate corresponding parts throughout, 10 designates in general the body of my heater which, as shown, is largely of the conventional type, comprising a conventional inner shell 11 and an outer shell 12 spaced therefrom. The inner shell is provided with the customary pump casing 13 having a pump 14 and is cored at one side as 50 at 15 to provide a discharge passage through which a molten metal is forced.

55 Extending outwardly from the inner shell

and insulated therefrom are spaced pins 16 between which are secured the magnetic cores 17 of the secondary winding 18 which winding, is short circuited upon itself and may be formed in one or more sections as desired, 60 each section having one or more turns. The cores of these coils are preferably formed of cast steel or other metal. Positioned above this secondary winding is an intermediate shell or casing 19, the inner face of which is 65 preferably adapted to reflect the heat generated in the secondary winding against the inner shell of the heater. Surrounding this intermediate casing is the primary winding 20 through which the current passes, said 70 primary winding being opened and closed by means of any suitable form of switch, not shown. An automatic switch or cut off, designated as a whole by the numeral 21 is also electrically connected with the primary 75 winding in such a manner as to automatically cut off the current through said winding when the temperature of the heater has reached a predetermined point as will be 80 hereinafter explained. As shown, a hot air 80 space is left above the coils and this space may be open at the top or not as desired. The secondary winding is preferably provided with a fuse 22 which will blow out if the induced current becomes too strong and 85 thus prevent the fusion of a winding. As will be apparent, the passage of an alternating current through the primary winding will induce a current in the secondary winding, thereby generating heat, the heat generated depending upon the strength of the 90 induced current.

Referring more specifically to the automatic switch which has been designated as a whole by the numeral 21, said switch will 95 be seen to consist of a plate of nonconductive material 23 mounted upon the upper edge of the inner shell 11 and carrying a pair of spaced contacts 24 which are electrically connected with the primary winding in such 100 a manner that the bridging of these contacts will close the circuit through said winding. Pivoted by one end to this plate is a switch bar 25, which normally bears across the contact pins 24 closing the circuit. Passing 105 through the plate 23 and immediately beneath the central portion of the switch bar is a bore which communicates with a bore formed in the inner shell of the heater, said latter bore being designated by the numeral 110

26 and terminating at its lower end in an
enlargement 27 cored in the shell of the
heater and forming a chamber or well which
is partially filled with mercury or other
5 highly expansible fluid. Positioned within
the bore 26 is a float 28 having a stem 29
which extends upwardly through an aperture
formed in the switch bar. The intermediate
portion of this stem is screw
10 threaded to receive a nut 30 which in normal
position bears upon the top of the shell and
supports the float. By adjusting this nut
the position of the float may be adjusted
at will. As will be readily seen the heat of
15 the inner shell will be communicated to the
mercury which will expand to come in con-
tact with the float and raise the same until
the nut 30 engages with the switch bar and
raises it, to open the switch. When the
20 switch has been so opened the heating cir-
cuit is opened and all further heating of the
metal is stopped. As soon as the metal be-
gins to cool, the mercury contracts thereby
closing the switch to again heat the metal.
25 By means of this automatic switch, there-
fore, it will be apparent that the metal
when once melted is maintained at a prac-
tically constant temperature and that this
temperature may be regulated by the ad-
30 justment of the nut 30.

From the foregoing description it will
be apparent that I have provided a simple
and effectual electric heater for type metal,
similar in all respects to the heater now in
35 use with the exception that the heat is gen-
erated electrically.

It will further be seen that I have pro-
vided a simple form of thermo actuated, au-
tomatic cutoff or switch for maintaining
40 the constant temperature in the heater and
for preventing unnecessary consumption of
current.

It will of course be understood, that minor
changes in the details of construction may
45 be made if desired without in the slightest

degree departing from the spirit of my in-
vention.

What I claim is:—

1. A type metal heater, comprising an
inner shell, a secondary winding about said 50
inner shell and insulated therefrom, a heat
reflecting shell surrounding said winding,
a primary winding about said reflecting
shell, and an outer shell about said primary
winding. 55

2. A type metal heater comprising an
inner shell and an outer shell spaced apart,
a secondary winding about said inner shell
and short circuited upon itself and insulated
from such inner shell, a reflecting shell sur-
rounding said secondary winding, a primary
winding about said reflecting shell and sur-
rounded by the outer shell, an automatic
switch for the primary winding, and a
thermo-actuated means for opening and 65
closing said switch. 60

3. In a device of the character described,
the combination with a body portion, in-
cluding a shell adapted to contain type
metal to be heated, said shell having a bore 70
extending longitudinally of the wall there-
of and a chamber in the wall with which
chamber the bore communicates, a primary
winding and a secondary winding surround-
ing the shell, of a switch for the primary 75
winding including a switch bar pivoted at
one end and apertured intermediate its
length, a float positioned in said bore, a
float stem carried by said float and extended
through the aperture of the switch bar, a 80
nut adjustable upon said stem and below
the switch bar, and a thermo expansible
liquid in said chamber.

In testimony whereof, I affix my signa-
ture, in presence of two witnesses.

DONALD S. KRAMER.
